UNITED STATES PATENT OFFICE

2,097,968

MINE CAR AND THE LIKE

Glenn E. Edmunds, Columbus, Ohio, assignor to
 The Bonney-Floyd Company, Columbus, Ohio,
 a corporation of Ohio

Application April 5, 1935, Serial No. 14,942
 Renewed February 27, 1937

29 Claims. (Cl. 105—364)

The present invention relates to improvements in wheel mounting means, body structure and in independent wheel suspension for vehicles and is particularly applicable to mine cars and the like. 5 The general suspension arrangement involved is that disclosed in my United States Patent No. 1,974,018, issued September 18, 1934.

According to the present invention, I provide self-contained, independent wheel housing and 10 mounting units. The wheel housings are preferably integral steel castings and are preferably so designed that, through reversal of the core in the casting operation, the two specific designs required for each car may be made without other 15 change.

A specific embodiment of the invention is shown by way of illustration in the accompanying drawings, in which

Figure 1 is a side elevation of a mine car embodying the invention;

Figure 2 is a section substantially on the line 2—2 of Figure 1;

Figure 2a is a section substantially on the line 2a—2a of Figure 1;

Figure 3 is a plan view, with parts broken away, of what is shown in Figure 2;

Figure 4 is a section substantially on the line 4—4 of Figure 3; and

Figure 5 is a section substantially on the line 30 5—5 of Figure 3.

Referring to the drawings, reference numeral 10 designates generally a mine car having a body comprising side walls as at 11, end walls 12 and 13, here shown as being of the vestibule type, and 35 a floor plate 14 which extends from side to side and from end to end of the car body, all portions of the plate, including the side portions as at 15, Figure 2, being preferably at the same level.

A pair of main sills as at 16 extend from end 40 to end of the car body in inwardly spaced relation to the side walls, the main sills being desirably constituted by bulb flanged angles having bottom flanges on top of the floor plate and secured thereto. The ends of the main sills are rigidly 45 connected by means of end sill and bumper structures 17 and 18.

The outer marginal portions of the floor plate rest on top of lower inwardly turned flanges of Z-bars as at 19 and are rigidly secured to the 50 latter, the Z-bars running from end to end of the car and constituting auxiliary sills and lower side wall portions tied in at their ends to the main sills through any suitable means such as the end walls. The top flanges of the Z-bars, which 55 extend outwardly from their vertical webs

as indicated in Figure 2, have secured thereto the horizontal flanges of angles as at 20, the vertical flanges of the angles being outward and having the lower margins of the side walls riveted thereto. At their intermediate portions, 5 the side walls are inwardly offset as at 21, Figure 2a, and Z-bars as at 22, running from end to end of the side walls, are secured over the offset as by welding in the position shown in Figure 2a. The bars as at 22 are engageable by rotary dumping mechanism. As the vein becomes thinner so that the vertical clearance is insufficient for the car, the end and side walls may be burned off above the level of the members as at 22 so as to reduce the height of the car. Since, through the 15 use of the Z-bars as at 19, the side walls as at 11 are in planes outwardly of the lateral edges of the floor plate, it will be evident that the capacity of the car is materially increased.

Immediately outwardly of the main sills, the 20 side floor portions as at 15 are each provided with a pair of longitudinally spaced wheel openings of which one is indicated by the reference numeral 23, Figure 2. A wheel housing and mounting unit 25 generally indicated by the reference numeral 24 is of inverted box-like formation having the end walls 25 and 26, the side walls 27 and 28 and the top wall 29. The top wall 29 has a central upwardly arched portion 30 which provides for adequate wheel clearance. The side wall 27 has prolongations 31 and 32 beyond the end walls 25 and 26, wall 27 resting against the flat outer face of the main sill 16, it and the prolongations 31 and 32 being riveted to the sill. Centrally, wall 28 is provided with an outwardly tapered downwardly open hollow extension 33, this extension and the wheel housing proper being provided at their lower edges with horizontally projecting flanges 34, 35, 36, 37, and 38, 39, the lower faces of these flanges lying in the same plane as the lower faces 40 of the horizontal flanges of the main sills. Flanges 36, 37, 38 and 39 are riveted to the side flooring 15 around the wheel opening 23, flanges 34 and 35 being riveted to that portion of the side flooring extending between the opening and the 45 side wall. At its extremity, extension 33 is closed by a vertical wall 40 extended laterally of the extension into flanges 41 and 42. The end wall 40 and flanges 41 and 42 abut the vertical web of Z-bar 19 and are riveted thereto.

Adjacent end wall 25, side walls 27 and 28 are inwardly thickened at 27a and 28a and are pierced at these thickened portions to provide openings in which are received the ends of a pivot bolt 43. Adjacent end wall 26, wall 28 is provided 55

with a downwardly projecting lug 44 which is provided with an elongated opening 44a, the bottom portion of the opening being below the side floor portion 15. A yoke generally designated at 5 45 and preferably made as a single piece steel casting, has a tubular portion 46 pivotally supported on bolt 43 through the intermediary of bushings 47 and 48. On its lower side, and intermediate the bushings, member 46 is desirably provided with a grease fitting 49. The ends of tubular portion 46 are just clear of portions 27a and 28a so that minimum axial displacement of portion 46 is permitted.

A pair of parallel arms 50 and 51 extend from 15 tubular portion 46 toward the housing end wall 26, the arms and the tubular portion being braced by the gusset 52. Halfway between the ends, as here shown, arms 50 and 51 are provided respectively with the inner and outer bosses 53, 20 54, and 55, 56. The inner bosses 53 and 55 have inner radially expanded portions 53a and 55a, the outer bosses 54 and 56 having similar radial expansions 54a and 55a, which, however, do not project below the bosses. The arms and bosses 25 are provided with aligned hexagonal openings which receive the ends of a hexagonal stub axle 57 which carries a flanged wheel 58, the wheel and axle assembly being that disclosed in my co-pending application Serial No. 599,552, filed March 30 17, 1932, now Patent No. 2,056,651 issued October 6, 1936. Obviously, the ordinary round stub axle could be substituted so that the invention is not limited in this respect. In assembly, the wheel 58 is placed between the arms and the axle inserted. With the devices in operative position, 35 housing walls 27 and 28 lie across the ends of the axle as particularly shown in Figure 5 so as to limit its axial displacement.

At their ends remote from bolt 43, arms 50 and 40 51 are joined at their lower edges by a substantially horizontal wall 59 on the upper face of which are formed spring centering bosses 60 and 61 adjacent arms 50 and 51, respectively. A vertical wall 62 connects arms 50 and 51 and the 45 inner edge of bottom wall 59, the central portions of walls 59 and 62 being joined by a vertical partition wall 63 as here shown, although this partition wall, if desired, may be replaced by another spring centering boss. The extremities of arms 50 and 51 and bottom wall 59 are joined by a downwardly projecting flange 64, Figures 2 and 4.

Spiral compression springs 65 and 66 have their lower ends engaged with bosses 60 and 61, the upper ends of these springs being engaged with 55 centering bosses 67 and 68, formed on the underside of housing wall 29 immediately above bosses 60 and 61. A system of friction blocks could be used instead of the simple springs, if desired.

Adjacent their extremities, arms 50 and 51 have outwardly projecting lugs 50a and 51a, respectively, lug 51a as here shown being opposite and above the lug 44 which depends from wall 28.

With the described parts in the position shown, a key 69 may be projected through the opening 65 44a of lug 44 so as to underlie lug 51a, the key having a body portion of the outline indicated in Figure 3 underlying flange 37 of the housing and riveted thereto through the side flooring portion 15. The key 69 limits movement apart 70 of the yoke and housing, as will be understood. Due to this limited range of relative movement, the axle 57 cannot pass below the retaining walls 27 and 28 so as to be displaceable to inoperative position. Movement of the yoke and housing toward one another is limited through abutment of 75

the upwardly offset extremities 50b and 51b of the arms and the top edge of wall 62 with the undersurface of the housing top wall 29. In taking lateral stresses, the hub portion of wheel 58 may bear against expansions 53a and 55a while expansions 54a and 56a may bear slidably against the inner faces of housing walls 27 and 28.

The wheel housing and mounting unit is preferably made as an integral steel casting. It not only provides a construction of great rigidity, 10 but is much more resistant than rolled metal to the action of corrosive waters often encountered in mines. Wall 62 of yoke 45 serves to prevent matter thrown by wheel 58 from striking and clogging springs 65 and 66. However, the 15 spring pockets are open at their outer ends so that any matter caught therein may pass out.

I have particularly described the wheel housing and mounting 24 at the right hand end of the car, Figure 1. As shown, the pivot bolt 43 is 20 toward the center of the car but it could of course be positioned toward the right hand end of the car. Exactly the same housing and mounting unit could be used for the left hand wheel 10, Figure 1, although in that case the pivot bolts 25 would both be to the left of the wheels, whereas, as shown, the pivot bolt 11 associated with the left hand housing 12 is toward the center of the car. Due to the symmetrical design of housing 24, to produce housing 12, it is merely necessary 30 to reverse the core, as will be understood. Yoke 45 may be used in either position, since it is entirely symmetrical and since each arm is provided with an abutment for cooperation with an abutment key 69. With the yoke arranged in 35 housing 12, the lug 50a will cooperate with the key, instead of lug 51a as shown in Figures 2, 3, and 4.

It will be understood that only two housing designs are required regardless of the positioning 40 of the pivot bolts at the ends of the housing. For example, on the opposite side of the car from that shown in Figure 1, a housing 24 would be used at the left and a housing 12 at the right and a similar rearrangement would follow if 45 the pivot bolts were disposed toward the ends instead of toward the center of the car. With the pivot bolts both toward the same end of the car, two identical housings would be used on one side of the car and two of the opposite design on the other side of the car.

In order to strengthen the side walls, the 50 housings may be connected to the same through gusset plates. In Figure 2, the casting is provided with a transversely extending fin 73 extending 55 from the arched portion 30 along the top of extension 33. A gusset plate 74 is riveted to fin 73 and has a turned flange 74a lying against side wall 11 and riveted thereto.

It will be understood that variations may be 60 made in the described parts and their arrangement without departure from the scope of the invention and that accordingly I do not limit myself except as in the following claims.

I claim:—

1. A mine car having an under-structure including a main sill and an auxiliary sill spaced outwardly from the main sill, said auxiliary sill comprising a vertical web and an inwardly turned flange, a wheel housing positioned between said 70 sills and having a portion secured to said main sill, said wheel housing having a rigid lateral extension extending to the auxiliary sill, said extension having a horizontal flange riveted to said inwardly turned flange and having at its 75

- outer extremity a vertical flange riveted to said vertical web, said housing having provisions for mounting a wheeled stub axle so as to constitute a self-contained wheel housing and mounting unit. 5
2. A mine car having an under-structure including a main sill and an auxiliary sill spaced outwardly from the main sill, said auxiliary sill comprising a vertical web and an inwardly turned flange, a wheel housing positioned between said sills and having a portion secured to said main sill, said wheel housing having a rigid box-like extension extending to the auxiliary sill, said extension having a horizontal bottom flange riveted 10 to said inwardly turned flange and having at its outer extremity a vertical flange riveted to said vertical web, said housing having provisions for mounting a wheeled stub axle so as to constitute a self-contained wheel housing and mounting 15 unit. 20
3. A mine car having an under-structure including a main sill and an auxiliary sill spaced outwardly from the main sill, a bottom floor including a central portion inwardly of the main 25 sill and a side portion extending between the sills, said floor portions being in the same plane and being secured to the sills at the lower portions of the latter, said side floor portion having a wheel opening adjacent the main sill, a wheel 30 housing closing said opening and extending above the plane of the floor, said housing having a rigid extension extending to the auxiliary sill, said housing being secured to the main sill and the housing and extension having bottom flanges secured to the side floor portion, the outer extremity 35 of said extension being secured to said auxiliary sill, said housing having provisions for mounting a wheeled stub axle so as to constitute a self-contained wheel housing and mounting unit. 40
4. A mine car having an under-structure including a main sill and an auxiliary sill spaced outwardly from the main sill, said auxiliary sill comprising a vertical web and an inwardly turned flange, a wheel housing positioned between 45 said sills and having a portion secured to said main sill, said wheel housing having a rigid lateral extension extending to the auxiliary sill, said extension having a horizontal flange riveted to said inwardly turned flange and having at 50 its outer extremity a vertical flange riveted to said vertical web, a pivot bolt supported by side walls of said housing, a wheel mounting yoke pivoted on said bolt, and yieldable means interposed between said housing and yoke remote 55 from the pivoting axis of the latter. 55
5. A mine car having an under-structure including a main sill and an auxiliary sill spaced outwardly from the main sill, a bottom floor including a central portion inwardly of the main 60 sill and a side portion extending between the sills, said floor portions being in the same plane and being secured to the sills at the lower portions of the latter, said side floor portion having a wheel opening adjacent the main sill, a wheel 65 housing closing said opening and extending above the plane of the floor, said housing having a rigid extension extending to the auxiliary sill, said housing being secured to the main sill and the housing and extension having bottom flanges secured to the side floor portion, the outer extremity 70 of said extension being secured to said auxiliary sill, a pivot bolt supported by side walls of said housing, a wheel mounting yoke pivoted on said bolt, and yieldable means interposed between 75
- said housing and yoke remote from the pivoting axis of the latter. 5
6. Wheel mounting means comprising a housing having top, end and side walls, a pivot bolt supported by the side walls of the housing adjacent one end of the latter, a yoke pivotally supported at one end on said bolt, yieldable means between the other end of the yoke and the top wall of the housing, the yoke having stub axle receiving recesses between its pivoting axis and said yieldable means. 10
7. A wheel housing according to claim 6 formed as an integral casting, wherein receiving means for the bolt may be formed in either end of the housing by reversing the core in the casting operation. 15
8. A wheel housing according to claim 6 formed as an integral casting, wherein receiving means for the bolt may be formed in either end of the housing by reversing the core in the casting operation, the yoke being symmetrical so as to be operatively pivotal in either end of the housing. 20
9. Wheel mounting means comprising a housing having top, end and side walls, a pivot bolt supported by the side walls of the housing adjacent one end of the latter, a yoke pivotally supported at one end on said bolt, yieldable means between the other end of the yoke and the top wall of the housing, the yoke having stub 25 axle receiving recesses between its pivoting axis and said yieldable means, and abutment means secured to a side wall of the housing and co-operating with an abutment portion of the yoke to limit movement apart of the housing and yoke. 30
10. Wheel mounting means comprising a housing having top, end and side walls, a pivot bolt supported by the side walls of the housing adjacent one end of the latter, a yoke pivotally supported at one end on said bolt, yieldable 40 means between the other end of the yoke and the top wall of the housing, the yoke having stub axle receiving recesses between its pivoting axis and said yieldable means, and abutment means secured to a side wall of the housing and co-operating with an abutment portion of the yoke to limit movement apart of the housing and yoke, said abutment means being in the form of a key riveted to the side wall and the abutment portion of the yoke being constituted by a laterally projecting lug. 45
11. Wheel mounting means comprising a housing having top, end and side walls, a yoke which has a pivoting axis adjacent one or the other of the housing end walls, yieldable means interposed between the free end of the yoke and the housing top wall, the yoke having stub axle receiving recesses which are half way between the housing end walls, regardless of which end of the housing the yoke is pivoted in. 55
12. Mounting means for a wheeled stub axle, said means comprising a yoke having arms extending side by side and having stub axle receiving recesses intermediate their ends, pivotal provisions at one end of the yoke, and a transverse 60 spring seating web connecting the arms at the other end of the yoke. 65
13. Mounting means for a wheeled stub axle, said means comprising a yoke having arms extending side by side and having stub axle receiving recesses intermediate their ends, pivotal provisions at one end of the yoke, a transverse spring seating web connecting the arms at the other end of the yoke, and a guard plate substantially perpendicular to said web at the 70 75

inner edge of the latter and connecting said arms. 14. Mounting means for a wheeled stub axle, said means comprising a yoke having arms extending side by side and having stub axle receiving recesses intermediate their ends, pivotal provisions at one end of the yoke, a transverse spring seating web connecting the arms at the other end of the yoke, and a guard plate substantially perpendicular to said web at the inner edge of the latter and connecting said arms, the web and guard plate constituting an upwardly and outwardly open pocket. 5

15. Mounting means for a wheeled stub axle, said means comprising a yoke having arms extending side by side and having stub axle receiving recesses intermediate their ends, pivotal provisions at one end of the yoke, a transverse spring seating web connecting the arms at the other end of the yoke, and abutment lugs on 20 the outer faces of the arms adjacent the free ends of the latter. 10

16. In combination, a housing comprising top, end and side walls, the side walls having inner surfaces in parallel planes, a pivot bolt extending between the side walls adjacent one of the end walls, a yoke pivoted on said bolt and having portions spaced from the bolt and close to said side wall surfaces for guided contact with the latter, a wheeled stub axle mounted in the yoke, 30 and yieldable means between the yoke and the housing top wall. 35

17. In combination, a housing comprising top, end and side walls, the side walls having inner surfaces in parallel planes, a pivot bolt extending between the side walls adjacent one of the end walls, a yoke pivoted on said bolt and having portions spaced from the bolt and close to said side wall surfaces for guided contact with the latter, a wheeled stub axle mounted in the yoke, 40 and yieldable means between the yoke and the housing top wall, and means fixed to the housing and engageable by the yoke to limit movement of the yoke away from said top wall. 45

18. In combination, a housing comprising top, end and side walls, the side walls having inner surfaces in parallel planes, a pivot bolt extending between the side walls adjacent one of the end walls, a yoke pivoted on said bolt and having portions spaced from the bolt and close to 50 said side wall surfaces for guided contact with the latter, said portions having aligned openings into which a stub axle may be introduced axially, a wheel stub axle in said openings and retained therein by said side wall surfaces, and 55 yieldable means between the yoke and the housing top wall. 55

19. In combination, a housing comprising top, end and side walls, the side walls having inner surfaces in parallel planes, a pivot bolt extending between the side walls adjacent one of the end walls, a yoke pivoted on said bolt and having portions spaced from the bolt and close to 60 said side wall surfaces for guided contact with the latter, said portions having aligned openings into which a stub axle may be introduced axially, a wheeled stub axle in said openings and retained therein by said side wall surfaces, yieldable means between the yoke and the housing top wall, and means fixed to the housing and 70 engageable by the yoke to limit movement of the yoke away from said top wall. 75

20. A mounting yoke for a wheeled stub axle, said yoke comprising parallel arms joined at one end and having pivoting provisions at said 75 end, and spring seating provisions at the other

end of said yoke, said arms having aligned axle-receiving openings substantially midway between said pivoting and seating provisions. 5

21. A mounting yoke for a wheeled stub axle, said yoke comprising parallel arms joined at one end and having pivoting provisions at said end, and spring seating provisions at the other end of said yoke, said arms having aligned axle-receiving openings substantially midway between said pivoting and seating provisions, said arms having outwardly projecting portions at said 10 openings for transmitting lateral thrusts. 10

22. In a vehicle comprising a lading body having a floor and side walls, main sills spaced inwardly from the side walls, the floor being provided with wheel openings between the sills and side walls, wheel mounting means at each opening and each comprising a housing extending between a sill and side wall and secured thereto and to the floor margins at an opening, an arm 15 pivotally mounted in the housing, a wheel carried by the arm at a distance from the arm pivot, and cushion means between the arm and a superjacent portion of the housing. 20

23. In a vehicle comprising a lading body having a floor and side walls, main sills spaced inwardly from the side walls the floor being provided with wheel openings between the sills and side walls, wheel mounting means at each opening and each comprising a housing extending between a sill and side wall and secured thereto and to the floor margins at an opening, an arm 30 pivotally mounted in the housing, a wheel carried by the arm at a distance from the arm pivot, cushion means between the arm and a superjacent portion of the housing, and means secured to the housing limiting movement of said arm under the action of said spring. 35

24. Wheel mounting means comprising a wheel housing, an arm pivotally mounted in said housing, a wheel in said housing carried by said arm at a distance from the arm pivot, and cushion means between the arm and a superjacent portion of the housing. 40

25. Wheel mounting means comprising a wheel 45 housing, an arm pivotally mounted in said housing, a wheel in said housing carried by said arm at a distance from the arm pivot, cushion means between the arm and a superjacent portion of the housing, and means secured to the housing limiting movement of said arm under the action 50 of said spring. 50

26. Wheel mounting means comprising a wheel housing, an arm pivotally mounted in said housing, a wheel in said housing carried by said arm at a distance from the arm pivot, said housing 55 having wall portions in guiding relation to said arm, and cushion means between the arm and a superjacent portion of the housing. 60

27. Wheel mounting means comprising a wheel 60 housing, an arm pivotally mounted in said housing, a wheel in said housing carried by said arm at a distance from the arm pivot, said housing having wall portions in guiding relation to said arm, cushion means between the arm and a 65 superjacent portion of the housing, and means secured to the housing limiting movement of said arm under the action of said spring. 70

28. In a vehicle, a lading body structure comprising main longitudinal sills and auxiliary 70 sills spaced outwardly from said main sills, side floor portions extending between the main sills and auxiliary sills, said floor portions being provided with wheel openings between the main and auxiliary sills, wheel mounting means at each 75

- opening and each comprising a housing extending between a main and an auxiliary sill and secured thereto and to the floor margins at an opening, an arm pivotally mounted in the housing, a wheel carried by the arm at a distance from the arm pivot, and cushion means between the arm and a superjacent portion of the housing. 5
29. In a vehicle, a lading body structure comprising main longitudinal sills and auxiliary sills spaced outwardly from said main sills, side floor portions extending between the main sills and auxiliary sills, said floor portions being provided 10
- with wheel openings between the main and auxiliary sills, wheel mounting means at each opening and each comprising a housing extending between a main and an auxiliary sill and secured thereto and to the floor margins at an opening, an arm pivotally mounted in the housing, a wheel carried by the arm at a distance from the arm pivot, cushion means between the arm and superjacent portion of the housing, and means secured to the housing limiting movement of said arm under the action of said spring. 10

GLENN E. EDMUND. S.
